Application October 19, 1949, Serial No. 122,285

7 Claims. (Cl. 112—231)

1

This invention relates to lock-stitch sewing machines, and more particularly to a lock-stitch machine of the type having a rotary hook with an open-sided raceway for the bobbin case, and having a full-floating bobbin case.

An object of the invention is to provide an improved lock-stitch machine of the above type, which is able to sew faster, that is, at higher speeds, than prior machines.

Another object of the invention is to provide an improved high speed lock-stitch machine as characterized above, which will sew more material before the bobbin becomes empty and requires replacement.

Essentially the speed of a sewing machine depends on the speed of the parts handling the thread, and the speed which can be imparted to the thread by these parts. Included in the parts which carry out critical thread-handling operations in a lock-stitch machine of the above type are the rotary hook, bobbin case, and the hanger for the latter, and the present invention is particularly concerned with improvements in these parts to enable the machine speed and thread capacity to be materially increased.

Heretofore, lock-stitch machines having full-floating bobbin cases employed a 3 to 1 ratio between the main shaft and the rotary hook. In these machines it was required to have a narrow gap ahead of the hook point in order to provide as much bearing or raceway surface in the hook for engagement by the segmental bearings on the bobbin case which are necessary to produce the full floating movement of the case. If it was attempted to use a wide gap, the bearing on the top of the hook would be decreased and the case would wedge and jam in the gap.

In such machines due to the impossibility of providing a wide gap in the hook ahead of the point, the encirclement of the bobbin case by the needle thread loop and separation of the loop from the bobbin case required at least one revolution of the sewing hook, this taking place under considerable speed when the machine is operating normally. For example, at a machine speed of 3400 R. P. M. the time which the needle thread loop is given, to encircle and leave the bobbin case, is on the order of $1/170$ of a second, due to the fact that the hook speed is 10,200 R. P. M. If such a machine is speeded up to 5,000 R. P. M. the hook speed becomes 15,000 R. P. M. and the time available for the needle thread loop to encircle and leave the bobbin case becomes $1/250$ of a second. With the terrific speeds and short time intervals encountered when

2

the machine speed is 5,000 R. P. M. the control of the sewing or stitching could not always be satisfactorily accomplished for all practical purposes because of difficulty in passing the loop in such a short time.

According to the present invention the above objects, i. e. faster machine speeds and greater thread capacity in the bobbin, are accomplished by changing the ratio of the machine to 2 to 1, so that the hook speed is only double that of the machine, solving the loop-passing problem, and by providing a novel hook, bobbin case and hanger structure whereby the needle thread loop is caused to leave the bobbin case, after encirclement thereof, sooner in the loop-passing cycle and whereby an improved balance and control means for a larger and heavier bobbin case is effected to prevent interference with the needle thread loop when it is encircling the bobbin case.

I have found that when a 3 to 1 ratio machine is changed to a 2 to 1 ratio, the time allotted to the needle thread loop to encircle and leave the bobbin case is proportionately more, and the time which remains for the take-up mechanism to operate after the encirclement by the needle thread loop is proportionately less to such an extent that the take-up mechanism does not always properly function. In other words, considering a 3400 R. P. M. machine speed, in a 2 to 1 ratio machine the hook speed becomes 6800 R. P. M. and the time for one revolution becomes $1/113$ of a second. Therefore this fraction of a second is the time given for the needle thread loop to encircle and leave the bobbin case, and is substantially longer than the $1/170$ of a second interval in a 3 to 1 ratio machine. However, whereas a 3 to 1 ratio machine provides $1/85$ of a second for the take up of the needle thread loop, the 2 to 1 ratio machine provides only $1/113$ of a second for the take-up mechanism, at machine speeds of 3400 R. P. M.

In accordance with the present invention I have devised a novel hook and bobbin case structure whereby the needle thread loop is caused to leave the bobbin case sooner than was heretofore possible. Thus I can reduce the time allotted to the operation of encircling the bobbin case by the needle thread loop, and can increase the time allotted for the take-up operation. I have found that since the changing of the machine ratio provides an excess over the amount of time required to encircle the bobbin case by the needle thread loop, this altering of the relative times which I have accomplished provides an ideal solution to the problem and enables much

higher machine speeds to be attained with satisfactory sewing characteristics. For example, at a machine speed of 5,000 R. P. M. one revolution of the hook at a hook speed of 10,000 R. P. M. occurs in $1/666$ of a second, and this may be compared with the $1/170$ of a second interval in a 3 to 1 ratio machine operating at a satisfactory sewing speed of 3400 R. P. M. I find that with my improved hook, bobbin case, and hanger construction I can satisfactorily operate a 2 to 1 ratio machine at a speed of 5,000 R. P. M., this being accomplished mainly by proper allocation or division of the time interval of $1/88$ of a second represented by two revolutions of the hook, between the loop passing operation and the take-up operation.

In the specific embodiment of the invention illustrated herein, I provide a cut-away portion on the rim of the hook raceway, extending for a distance ahead of the hook point, and provide a second cut-away portion in the upper flange section of the bobbin case, adapted to cooperate with the cut-away part of the hook whereby during part of each revolution of the hook a simulated wide gap exists between the upper portions of the hook and the bobbin case, resulting in the needle thread loop passing out through this wide gap at a time relatively early in the sewing cycle and substantially in advance of the hook completing one revolution in said cycle. This novel means of providing a so called wide gap in hook, does not reduce the necessary bearing surface for the floating case as explained earlier. It does however reduce the width of the bearing surface but as the bearing flanges on the bobbin case are made proportionately wide, said reduction has no ill effect.

As a consequence of the greater time allowed for the needle thread loop to encircle the bobbin case even when this time is thus shortened, the sewing function of the hook and bobbin case is made less critical, and consequently a larger bobbin case may be used, and a larger bobbin having a substantially increased thread capacity. Since the bobbin case is of the full floating type, this change will not materially increase friction or wear.

The increase in thread capacity may be as great as 45 to 50 per cent over the capacity heretofore considered the maximum in a 3 to 1 ratio machine. To eliminate interference with the needle thread loop during its movement in encircling the larger and heavier bobbin case, I provide an improved control and bearing means between the bobbin case and the hanger therefor, to cause the swing or oscillation of the bobbin case to be out of a vertical line and more in a horizontal plane. In effecting this, I provide a land or bearing surface at the lower portion of the bobbin case for engagement with the bobbin case hanger, which land is offset or located to one side of a vertical center line passing through the bobbin case. A similar offset land or bearing surface is provided at the upper portion of the bobbin case which is located on the opposite side of the vertical center line. I have found that these offset lands prevent swinging movement of the bobbin case about a purely vertical axis, and instead cause a swinging of the case about an axis disposed at a wide angle to the vertical, thereby resulting in less tendency to pinch the needle thread loop between the bottom portions of the bobbin case and the hanger.

In conjunction with the above structure I provide an improved needle shield in the bobbin case

which prevents inadvertent striking of the needle by the hook point and consequent damage to these parts, and this is an important feature of the invention.

Other features and advantages will hereinafter appear.

In the accompanying drawings:

Figure 1 is a side elevational view of the improved hook, bobbin case and hanger structure of this invention mounted in a sewing machine, a portion of the machine bed being shown in vertical section.

Fig. 2 is a top or plan view of the hook, bobbin case and hanger of Fig. 1.

Fig. 3 is an elevational view of the outer side of the bobbin case of this invention, and

Fig. 4 is an end elevational view of the rotary hook.

Fig. 5 is a section taken along line 5-5 of Fig. 3.

Referring to Fig. 1, the present improved novel, high-speed hook, bobbin case and hanger structure is mounted on the bed 10 of a sewing machine in operative position below a cloth plate 11. A hook shaft 12 is journaled in the bed 10 and at its protruding end mounts a hub 13 carrying a rotary hook 14 which is in the form of a relatively shallow cup.

The hook 14 is of the open raceway type, that is, it has an annular wall portion 15 constituting a circular raceway which is open at the side. As shown in Figs. 1 and 4 the hook 14 has a hook proper or point 16 adjacent an angularly disposed thread slot 17, the latter extending inside of a curved shield 18 which is secured to the exterior of the hook wall 15.

Inside the rotary hook 14 a bobbin case 19 is loosely carried, the said case being held in operative position by a hanger 20 having a shank 21 which is secured to a hanger arm 22 pivotally connected with a hanger bracket 23 attached to the underside of the bed 10. The bobbin case 19 has a loop check notch 24 in its upper portion, which loosely receives a loop check or projection 25 on the hanger 20. As is well understood, engagement between the loop check 25 and the wall 26 of the loop check notch 24 prevents the bobbin case 19 from turning when the rotary hook 14 is operating.

As above mentioned I have found that materially greater machine speeds may be attained with satisfactory sewing, when the present improved hook, bobbin case and hanger structure are incorporated in a 2 to 1 ratio machine, wherein the rotary hook makes two revolutions for each revolution of the main machine shaft.

In accordance with the present invention the hook 14, bobbin case 19 and hanger 20 are so constituted that the needle thread loop when encircling the bobbin case leaves the latter very soon in the sewing cycle, prior to the hook passing through one complete revolution (which occurs in one-half of said cycle). Thus more time is available for the take-up mechanism of the machine to pull the loop tight. Also, by the organization which I have provided, there is no interference with the needle thread loop as the latter is passed around the bobbin case at high speeds. Therefore the loop will not only be quickly separated from the bobbin case, but it will not be delayed or hampered in its travel around the case, and as a consequence, satisfactory sewing at relatively high speeds may be readily performed.

In accomplishing this, referring to Figs. 1, 2

and 4, I cut back an edge portion of the raceway 15 of the hook, at a location immediately ahead of the hook point, to provide a peripherally-extending elongate relatively narrow indentation 27 in the rim of the hook, the said indentation extending between the two radial dot-and-dash lines 28 and 29 shown in Fig. 4. The angle between the radial lines 28 and 29 is approximately 120°, indicating that the indentation extends about one-third of the way around the periphery or rim of the hook 14.

As shown in Fig. 2, I also provide a second indentation 30 in the upper portion of the bobbin case 19, by cutting away parts of a flange section 31 of said bobbin case forming the segmental bearings therefor. The remaining uncut or end portions of the flange section 31 are adapted to engage a circular shoulder 32 located on the inside of the raceway 15 of the hook 14. The cutting away of the flange section 31 thus provides clearance or space without reducing the bearing for the casing engaging at the shoulder 32.

The indentations 27 and 30 are so located that prior to the hook point 16 of the rotary hook reaching its uppermost position wherein it takes off the needle thread, the indentations will be alongside of each other, and will cause a simulated wide gap to exist between the hook and bobbin case at these points while retaining requisite bearing engagement. This wide gap enables the needle thread loop to leave the bobbin case very quickly after it has encircled the same, and therefore gives the take-up mechanism of the sawing machine more time to take up or pull the loop tight. This is extremely important for the reason that in a 2 to 1 ratio machine where the rotary hook 14 will rotate twice as fast as the main machine spindle, the time during which the take-up mechanism may act is considerably reduced over that provided in a 3 to 1 ratio machine, where encirclement of the bobbin case occurs in a much lesser time. It will be understood that if encirclement of the bobbin case occurs in the first revolution of the sewing hook, in the sewing cycle, there remains in a 3 to 1 ratio machine two revolutions of the hook during which the take-up of the loop would be accomplished. In a 2 to 1 ratio machine, if encirclement occurs in the first revolution of the hook, there remains only one other revolution of the hook during which the take-up of the loop may be effected. Thus the matter of having the loop leave the bobbin case very quickly after the encirclement of the case is of extreme importance in providing additional time for the take-up mechanism to act.

Where a 2 to 1 ratio is employed between the hook and the main shaft of the sewing machine, the hook speed for any given machine speed will be much less than where a 3 to 1 ratio is employed. Therefore with this lesser speed the sewing function involving the encirclement of the bobbin case by the needle thread loop is not so critical. As a consequence, the size and weight of the bobbin case may be increased, enabling the use of a larger bobbin holding more thread, and this is an important advantage where a machine is to be run at higher speeds, since in terms of elapsed time it means that empty bobbins will not have to be replaced by full bobbins so frequently.

However, when a larger or wider bobbin and a heavier case are used to provide more thread capacity, the balance of the case is upset. The matter of proper balance and suspension of the

case is extremely important, since an improper balance will result in interference with the needle thread loop as it encircles the case.

In accordance with the present invention I provide an improved means for balancing and controlling the movements of the bobbin case during the sewing operation whereby heat and friction are minimized, and whereby no interference is met by the needle thread loop during its encirclement of the case at high sewing speeds. To accomplish this result the bobbin case 19 must be suspended in the hook 14 to be full floating during the operation of these parts, and I arrange the bearing means for the case so that its swinging or oscillating movements are about a non-vertical axis. Accordingly, referring to Figs. 2 and 3, I offset the loop check 25 from the center a slight amount, and also the loop check notch 24 which receives the loop check. The amount of offset is such as to bring the other wall 33 of the notch 24 almost directly under the needle hole 34 in the cloth plate 11, this positioning enabling the bobbin thread 35 which passes upward inside of, and in engagement with, said wall to extend vertically to the center of the needle hole.

As clearly shown in Fig. 3 the bobbin thread 35 passes inside of a self-threader hook 36 through notch 36a from a tension spring 37 carried on the exterior of the bobbin case.

The notch, as shown in Fig. 5, is lower than the edge 36b of the hook 36, the hook tapering to this edge so that as a thread in the notch is drawn upwardly across the face of the case it automatically engages the tapered face 36c and moves under the hook 36 to the space therebehind whereupon it snaps into overlying relation as shown in Fig. 3.

By the above location of the wall 33 of the loop check notch 24 the bobbin case 19 is suspended from the thread 35 substantially vertically below the needle hole 34 of the cloth plate.

In conjunction with the above suspension of the bobbin case below the needle hole, a bottom case stop 38 is provided on the lower portion of the case, Fig. 3, the said stop being in the form of a raised portion or land extending in a circumferential direction and disposed mainly to one side of the vertical central transverse plane of the bobbin case. In other words, the land 38 is disposed substantially wholly to the left of the vertical center line 39 (Fig. 3) which passes through the axis of the case and through the inside surface of the wall 33 of the loop check notch 24. The land 38 is adapted to engage the lower portion of the hanger 20 as shown in Fig. 1, the upper portion of the hanger 20 extending below and engaging a curved shoulder 40 of the bobbin case to support the latter in suspension when the machine is at a standstill and the parts are not operative.

The offset position of the land 38 as provided by the present invention is extremely important in enabling high machine speeds to be attained in that it provides a control over the tilting movement of the bobbin case when the latter is suspended from the bobbin thread 35 which control results in the needle thread loop meeting with no interference as it is passed around the bobbin case by the rotary hook. In its suspended state, during the operation of the sewing machine, the bobbin case 19 tilts and oscillates within a very restricted path, and the offset position of the land 38 causes the bobbin case to tilt or swing about an axis other than vertical. This minimizes any tendency for pinching of the

needle thread loop between the lowermost portions of the hanger 20 and the bobbin case 19.

As shown in Fig. 3 additional lands 41 and 42 are provided on the bobbin case. The bobbin thread 35 passes over the land 41 and normally prevents engagement between said land and the upper portion of the hanger 20. The land 42 however may engage the upper portion of the hanger 20, and it will be obvious that this land is practically diametrically opposite the land 40 and is wholly to the right of the center line 39 of the bobbin case. The combined effect of the lands 38 and 40 in conjunction with the suspension provided by the bobbin thread 35 results in the bobbin case 19 having a swinging movement about an axis which is noncoincident with the vertical center line 39 shown in Fig. 3, and therefore the lower land 38 of the bobbin case will not be in engagement with the lower part of the hanger 20 except for extremely limited periods of time. Thus the needle thread loop may readily pass between the land 38 and the lower portion of the hanger 20 with practically no interference which might adversely affect the sewing operations of the machine. I have therefore provided by the above organization in a 2 to 1 ratio lock-stitch machine, a full floating bobbin case which in its action readily enables the needle thread loop to encircle the case without difficulty at relatively high sewing speeds.

The remaining wall 43 of the flange section 31 may be advantageously employed in conjunction with a sloping surface 44 in the bobbin case 19 to act as a guide for the needle of the machine when the latter is extended through the cloth plate 11. This guide prevents the needle from being struck by the hook point 16 of the rotary hook, and prevents consequent damage to the needle and hook.

A second shield is provided for the needle of the machine, indicated at 45 in Fig. 2, the said shield constituting the center wall of the loop check notch 24 of the bobbin case.

Variations and modifications may be made within the scope of the claims and portions of the improvements may be used without others.

I claim:

1. In a sewing machine having a rotary hook provided with an open-sided raceway, and having a bobbin case in said raceway provided with a loop-check notch and with a flange section extending past said notch and along the periphery of the case to guide the same in said raceway, the improvement which comprises: the edge of said raceway ahead of the hook being cut back to provide a peripherally extending, elongate, relatively narrow indentation, and said flange section of the case adjacent the loop-check notch being cut away to provide a second peripherally extending, elongate, relatively narrow indentation on its inner side whereby for part of a revolution of said hook prior to the hook point reaching its pick-off position a wide gap exists between the hook raceway and the bobbin case to enable the needle thread loop to leave the bobbin case relatively soon in each sewing cycle of the machine.

2. In a sewing machine having a rotary hook provided with an open-sided raceway, and having a bobbin case in said raceway provided with a flange section extending along the top peripheral portion of the case to guide the same in said raceway, the improvement which comprises: the edge of said raceway ahead of the hook being cut

back to provide an elongate, relatively narrow indentation extending peripherally through an arc greater than 90°, and said flange section of the case being cut away to provide a second peripherally extending, elongate, relatively narrow indentation on its inner side whereby for part of a revolution of said hook prior to the hook point reaching its pick-off position a wide gap exists between the hook raceway and the bobbin case to enable the needle thread loop to leave the bobbin case relatively soon in each sewing cycle of the machine.

3. In a sewing machine having a rotary hook geared to twice the machine speed and provided with an open-sided raceway and a shoulder therein, and having a bobbin case in said raceway provided with a peripherally-extended flange along its top for engagement with said shoulder to guide the case in the raceway, the improvement which comprises: the edge of said raceway ahead of the hook being cut back part way to said shoulder to provide a peripherally extending elongate relatively narrow indentation, and said flange being cut away for part of its length adjacent the shoulder to clear the same and provide another elongate, relatively narrow indentation whereby for part of a revolution of said hook prior to the hook point reaching its pick-off position a wide gap exists between the hook raceway and the bobbin case to enable the needle thread loop to leave the bobbin case relatively soon in each sewing cycle of the machine.

4. In a sewing machine having a rotary hook provided with an open-sided raceway, and having a bobbin case in said raceway provided with a flange section extending along the top peripheral portion of the case to guide the same in said raceway, the improvement which comprises: the edge of said raceway ahead of the hook being cut back to provide a peripherally extending, elongate, relatively narrow indentation, and said flange section of the case being cut away to provide a second peripherally extending, elongate, relatively narrow indentation on its inner side whereby for part of a revolution of said hook prior to the hook point reaching its pick-off position a wide gap exists between the hook raceway and the bobbin case to enable the needle thread loop to leave the bobbin case relatively soon in each sewing cycle of the machine; and means on said bobbin case, including the said cut-away flange section thereof, for guiding the needle of the machine to maintain said needle out of the path of the hook.

5. A bobbin case having a notch at one side thereof, an inwardly projecting self-threader hook adjacent the notch, said hook tapering to an inwardly facing edge located in a plane above the bottom of the notch and engaging a thread extending from the notch as the thread is moved upwardly across the case to automatically pick up and guide the thread to the rear of the hook and into threaded relation therewith.

6. In a sewing machine having a rotary hook provided with a wall forming an open-side raceway, and having a bobbin case in said raceway provided with a flange section extending along the top peripheral portion of the case to guide the same in said raceway, the improvement which comprises: the edge of the wall forming said raceway ahead of the hook being cut away to provide a peripherally extending, elongate, relatively narrow indentation less than the depth of said flange section, and said flange section of the case being partially cut away on the inner side centrally

thereof to provide a second peripherally extending, elongate, relatively narrow indentation whereby for part of a revolution of said hook prior to the hook point reaching its pick-off position, said cut away portions overlap and form a wide gap between the hook raceway and the bobbin case to enable the needle thread loop to leave the bobbin case relatively soon in each sewing cycle of the machine.

7. In a sewing machine having a rotary hook provided with a wall forming an open-side raceway, and having a bobbin case positioned in said hook for movement transversely of the axis of the hook and floatingly supported in said raceway by a hanger when the needle thread is free to take-up tension, said casing being provided with a flange section extending at least along the top peripheral portion of the case to guide the same in said raceway, the improvement which comprises having the edge of the wall forming said raceway ahead of the hook cut away to provide a peripherally extending, elongate, relatively narrow indentation less than the depth of said flange section, and having said flange section of the case partially cut away on the inner side centrally thereof to provide a second peripherally extending, elongate, relatively narrow indentation, said cut away portions overlapping and

10

5 forming a wide gap between the hook raceway and the bobbin case for part of a revolution of said hook prior to the hook point reaching its pick-off position and while the casing is supported on the hanger to enable the needle thread loop to leave the bobbin case relatively soon in each sewing cycle of the machine, said flange and raceway providing bearing means therebetween when the bobbin case is lifted from the hanger by the take-up tension in the needle thread during a subsequent part of the revolution of said hook.
